(57) CLAIM

The ornamental design for a pet toy, as shown and described.

DESCRIPTION

FIG. 1 is a top perspective view of a pet toy embodying my design;

FIG. 2 is a bottom perspective view of the pet toy of FIG. 1;

FIG. 3 is a front elevational view of the pet toy of FIG. 1; FIG. 4 is left side elevational view of the pet toy of FIG. 1; FIG. 5 is a right side elevational view of the pet toy of FIG. 1;

FIG. 6 is a top plan view of the pet toy of FIG. 1;
